Patented Nov. 28, 1922.

Inventor
THOMAS B. HUESTIS

By his Attorney

Ernest Hopkinson

UNITED STATES PATENT OFFICE.

THOMAS B. HUESTIS, OF BRISTOL, RHODE ISLAND, ASSIGNOR TO REVERE RUBBER COMPANY, A CORPORATION OF RHODE ISLAND.

FEED MECHANISM.

Application filed April 23, 1920. Serial No. 378,005.

To all whom it may concern:

Be it known that I, THOMAS B. HUESTIS, a citizen of the United States, residing at Bristol, county of Bristol, and State of Rhode Island, have invented certain new and useful Improvements in Feed Mechanism, of which the following is a full, clear, and exact description.

This invention relates to a feed mechanism, more particularly to a means for feeding material, such as sheet rubber, to a die or other machine which is to operate upon the material.

An object of my invention is to provide a simple, efficient, positive and adjustable means for intermittently feeding a sheet of stock to a die or other mechanism for operating on the stock.

Another object of my invention is to prevent any retrograde movement of the stock in the intervals when it is not being fed forward.

A further object of my invention is to maintain the stock flat upon the work bed until acted upon by the die or other device.

For a complete disclosure of the invention reference is had to the accompanying specification and drawings, in which latter—

Figure 1 is a perspective showing the application of the feed mechanism to a die for cutting out rubber heel blanks; and

Figure 2 is a detail partly in section.

Referring to the drawings, the numeral 1 represents the frame of a die mechanism having a bed 2 over which the sheet stock is fed beneath the die head 3, the stock being then delivered by the inclined apron 4. At each side of the bed 2 are walls 5 having guideways 6, in which are mounted to slide the bearing blocks 7 of rock shaft 8. Rigidly and adjustably secured to the rock shaft, and extending forwardly in the direction of the die, are a series of arms 9, each of which carries a stock engaging and feeding finger 10. Also rigidly and adjustably secured to the rock shaft 8 adjacent the side walls 5 are rock arms 11, which extend outwardly over the walls 5 and then downwardly, terminating in rearward extensions 12, with which cams 13, mounted on a shaft 14, are adapted to contact. One end of the shaft

14 is provided with a bevel gear 15, with which is adapted to mesh a bevel gear 16, mounted on one end of shaft 17. The shaft 17 carries a sprocket 18 which is driven by a chain 21 from a sprocket 19 mounted on the main shaft 20 of the die apparatus. Any other suitable means for driving the shaft 14 may be used. The shaft 14 also carries at its end opposite the bevel gear 15 an eccentric 22, the strap 23 of which has an arm 24 pivotally connected with a rock arm 25, rigidly mounted on rock shaft 26. The throw of the eccentric may be varied by securing the arm 24 at different points in the adjusting slot 27 of arm 25, and a scale 28 is provided to aid in making such adjustment. Also rigidly connected to the rock shaft 26 is a rock arm 29 extending upwardly adjacent the rock arm 11 and having a slot 30 through which a pin 31 secured on the arm 11, may project. The arm 11 is yieldably urged in opposition to the cam 13 by means of the coil spring 32, having its ends secured to the rock shaft 26 and pin 31.

A pair of rearwardly extending arms 33 are secured to the sides of the machine bed adjacent the die head and their free ends are connected by a shaft 34, upon which are loosely mounted the bearing collars 35 of a series of toothed work engaging fingers 36. At one side of each collar 35 a collar 37 is rigidly secured as by a set screw to a shaft 34, and a coil spring 38 surrounds the shaft between the collars, its ends being secured to the respective collars 35 and 37. At the other side of each collar 35 a second collar 39 is rigidly secured by a set screw to shaft 34, and a pin 40 carried by the collar 39 is adapted to project into a limiting groove 41 in the collar 35. It will be seen from the drawings that the coil spring 38 tends to urge the work engaging finger 36 in a rearward direction or toward the feed mechanism, and the movement of the finger 36 in either direction is limited by the pin 40 contacting with the ends of the groove 41. In the particular embodiment shown, the feed device is applied to a gang die for dieing out blanks for rubber heels, but it is evident that it is capable of general application.

In operation a sheet of rubber stock is fed beneath the stock engaging fingers 10 and the machine started. By means of the cams 13 the rock arms 11 will be titled upwardly, rocking shaft 8, and thereby moving the fingers 10 carried by arms 9 downwardly into engagement with the stock, while at the same time the eccentric 22 through its strap 23 and arms 24, 25 and 29, 5 and the pin 31 will impart a translatory movement to the rock shaft 8 and supported parts forwardly toward the die, carrying the sheet stock into cooperation with the die. At the completion of the feed or forward movement the cams 13 allow the rock arms 11 to move downwardly again in response to the action of the coil spring 32, and the eccentric 22 through the previously recited connections, withdraws the feed 10 mechanism. The toothed stock engaging portions of the stock engaging fingers 36 are slightly curved upwardly at their rear ends and as the stock passes beneath the fingers 36 they are dragged forwardly with 15 it to a slight extent in opposition to the coil springs 38. However, if during a retracting movement of the feed mechanism there is any tendency of the sheet stock to move rearwardly, the coil springs 38 cause 20 the forward toothed portions of the fingers 36 to jam against the stock, thereby preventing any rearward movement. It will be noted that the fingers 36 are disposed relatively close to the feed fingers 10, so 25 that in addition to preventing retrograde movement of the stock they also maintain the stock at all times in contact with the bed, particularly at the time the fingers 10 are being disengaged from the stock after 30 a forward movement thereof. The collars 37 and 39 at each side of a bearing collar 35 are illustrated as somewhat widely spaced from the collar 35 in order to more clearly disclose the construction, but in practice 35 they will, of course, be secured to the shaft 34 closely adjacent to the collar 35 in order to prevent unnecessary side movement of the latter.

While a specific application of the feed 40 mechanism has been shown, it is not limited in its broad aspects to the particular construction described and illustrated, but may be used wherever it is desired to feed a sheet material, with such obvious modifications 45 of the stock engaging fingers 10 as the particular material used may necessitate.

Having thus described my invention, what I claim and desire to protect by Letters Patent is:

60 1. A feed mechanism for sheet rubber stock comprising a bed, transversely spaced stock feeding means disposed above the bed and slidably mounted at each side thereof, a shaft, and separate operating connections 65 from the shaft to the feeding means for

simultaneously moving the feeding means into contact with the stock and also forwardly.

2. A feed mechanism for sheet stock comprising a bed, a rock shaft mounted above the bed, stock engaging means rigidly carried by the rock shaft and cooperating with the bed to feed the stock, and means connected to said rock shaft for imparting to it a rocking motion and a reciprocatory motion transversely to its axis. 70

3. A feed mechanism for sheet stock comprising a bed, guideways at the sides of the bed, a rock shaft journaled to slide in said guideways, stock engaging means fixedly mounted on said shaft, a rock arm connected to said shaft, and means for rocking and also bodily moving said arm. 80

4. A feed mechanism for sheet stock comprising a bed, a rock shaft mounted in slideable bearings above said bed, means secured to said shaft carrying stock engaging fingers, rock arms secured to said shaft, yielding means secured to one of said arms for holding said fingers elevated, means for intermittently rocking said arms to cause the fingers to engage the stock, and means connected to one of said arms for imparting a translatory movement thereto. 90

5. A feed mechanism for sheet stock comprising a bed, guideways at the sides of and above the bed, a stock feeding means mounted in said guideways, cam arms carried by the stock feeding means, a shaft, cams thereon adapted to actuate the cam arms, and means carried by the shaft for imparting a translatory movement to the cam arms. 95

6. A feed mechanism for sheet stock comprising a bed, a drive shaft extending transversely below the bed, a rock shaft slidably mounted above the bed, feed means carried by the rock shaft, and operating connections between the shafts for imparting a plurality of movements to the feed means. 105

7. In a machine for dieing out rubber heel blanks from sheet stock, a bed, and means for intermittently advancing a sheet of stock over the bed comprising stock gripping means, a rock shaft, a rock arm on said shaft having a slidable connection with the stock gripping means, a second rock arm on said shaft, a drive shaft, means carried thereby for tilting the stock gripping means into engagement with the stock, and an adjustable driving connection between the drive shaft and second rock arm. 110

8. In a feed mechanism for sheet rubber stock, the combination of a bed, a reciprocatory and oscillatory feed mechanism for advancing the stock on the bed and including a series of pointed fingers adapted to enter the stock, and means including a series of movably mounted toothed fingers cooperating with the bed for preventing backward movement of the stock and maintaining the 125 130

latter in contact with the bed when the feed mechanism is retracted.

9. In a feed mechanism for sheet rubber stock, the combination of a bed, feed means cooperating therewith including a series of stock-piercing fingers and having stock advancing and return movements, a plurality of pivotally mounted toothed fingers in spaced relation to the feed means, yielding

means tending to press said fingers firmly into engagement with the stock upon a retrograde movement of the latter, and means for varying the pressure of said last named means.

Signed at Bristol, Rhode Island, this 30 ¹⁵ day of March, 1920.

THOMAS B. HUESTIS.
